UNITED STATES PATENT OFFICE.

ABRAHAM L. ROSENTHAL, OF CHICAGO, ILLINOIS.

DESIGN FOR A BOOK-COVER BLANK.

SPECIFICATION forming part of Design No. 31,380, dated August 8, 1899.

Application filed June 26, 1899. Serial No. 721,969. Term of patent 3 $\frac{1}{2}$ years.

To all whom it may concern:

Be it known that I, ABRAHAM L. ROSENTHAL, a citizen of the United States, residing at Chicago, county of Cook, and State of Illinois, have invented and produced a new and original Design for Book-Cover Blanks, of which the following is a specification, reference being had to the accompanying drawing, which shows a plan view of the design.

10 The drawing represents a blank of paper or other suitable covering material.

The leading feature of the design consists in a body portion A of sufficient size to receive the open book, the side-edge-infolding lobes a, the top and bottom edge infolding lobes a', 15 the smaller middle or back lobes a², and the dotted or puncture lines a³, extending in-

wardly from the ends of the curved lines bounding the lobes a². As thus described, the blank departs from the rectangular form in 20 the absence of corners at b, in the absence of material at b', adjacent to the middle lobes a², and in the presence of curved-line edges at the top, sides, and bottom, as shown.

Having described my invention, what I 25 claim as new, and desire to secure by Letters Patent, is—

The design for a book-cover blank substantially as herein shown and described.

ABRAHAM L. ROSENTHAL.
